UNITED STATES PATENT OFFICE.

BELLVILLE L. RANDALL, OF BOSTON, MASSACHUSETTS.

BRAKE FOR ELECTRIC CARS.

SPECIFICATION forming part of Letters Patent No. 444,110, dated January 6, 1891.

Application filed September 11, 1890. Serial No. 364,625. (No model.)

To all whom it may concern:

Be it known that I, BELLVILLE L. RANDALL, a citizen of the United States, residing at Boston, in the county of Suffolk and State of Massachusetts, have invented certain new and useful Improvements in Car-Brakes; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to car-brakes, particularly those applied on cars in which electricity is employed as the motive power.

My improvements consist in such mechanism as will enable the driver of an electric car, when he applies the brake, to automatically and simultaneously cut off the power. Thus, since any application of the brake necessarily calls for a diminution of the motive power, the driver is not obliged to direct a thought to the act of shutting off the power, but merely applies the brake to suit an emergency. This shutting off of the current is governed directly by the action of the brake—that is, the harder the latter is applied the more quickly is the motive power reduced or rendered nothing.

The drawings represent in Figure 1 a plan of a brake embodying my invention applied to an electric car. Fig. 2 is a vertical section through the power and brake drums. Fig. 3 is an enlarged view in plan of the brake and power drums, showing the position of the engaging lugs when the brakes are off and the power not applied.

In the drawings accompanying this specification I have represented in plan one end of a street-car 2, with the usual girders and tie rods, the floor being removed. Since the ends of this class of cars are duplicates in construction, but one end is shown for purposes of illustration. On the front end and exteriorly of the dasher 3 are mounted two shafts or rods 4 5, furnished with suitable hand-levers or cranks (not shown) by which they are revolved. These rods are termed, respectively, the "power" and "brake" rods, since by means of the former the current or

amount of force put in action is regulated. By the latter the friction applied to the wheels is controlled. In connection with the power-rod is a switch 6 for directing the current in 55 order to advance or to back the car. Furthermore, beneath the car and suitably mounted is a pendent shaft 8, upon which is loosely affixed a revoluble drum, (indicated at 9 as the upper one, and styled the "brake-drum," since 60 it is connected by a chain or band 10 with the brake-rod.) Exteriorly of said shaft is placed a loose sleeve 12, upon which is fastened a second drum 13, similar to that represented at 9, and which is termed the "power-drum," 65 the latter being actuated by the power-rod through the agency of a band or chain 14 and serves to control the speed of the car. This result is obtained as follows: A radial arm or lever 15 is secured to the sleeve 12 and 70 by the motion of the latter, produced by the drum and the operation of the band 14, is caused to co-operate with a rheostat, (indicated at 16.) This apparatus is attached at the end of the shaft 8, which supports it. 75

The resistances of the above mechanism can be thrown in and out of the main circuit with the evident result of regulating the amount of current flowing therein. This lever 15 swings in a horizontal plane and moves 80 over the various contact-segments composing the rheostat. However this forms no part of my invention, and any further description will be unnecessary.

The primary object of my invention is to 85 control the motive power by means of the brake, while at the same time not prevent the power-rod from exercising its usual function. To accomplish this result, I have connected the brake-rod 5 by means of an endless band 90 or chain 10 with the brake-drum and, moreover, secured an abutment 17 on its lower side. This abutment is adapted to contact with a corresponding ledge or shoulder 18 upon the upper side of the power-drum. As a result, 95 it is evident that rotation of the brake-rod to set the brakes will likewise revolve the brake-drum and cause the power-drum to be operated, swinging the lever-arm 15 to create such resistance on the rheostat as will effectually 100 check the current. Thus simultaneously with the application of the brake the motive power

is diminished, and hence in a case of emergency the attention of the driver is not diverted, in order to first cut off the power and then set the brake.

- 5 It is to be understood that the position of the brake-drum and its lug are such that no movement of the power-drum occurs unless the power is applied; but should the power be applied the lug 18 on the power-drum is then 10 in position to be engaged by the lug on the brake-drum when the rheostat-lever is operated by the rotation of the brake-rod. As soon as the brakes are off the brake-drum is returned to its normal position, as shown in 15 Fig. 3, in readiness to cut off the power whenever the brakes are again applied. By such an arrangement it is very evident the power-rod is free to move the power-drum and rheostat-lever without interference or hindrance 20 by the brake-drum and its operating mechanism.

In Fig. 1 is shown a modified form of arrangement. In lieu of connecting the brake-rod by the chain 10 with the brake-drum, the 25 chain 10 and the brake-drum 9 may be omitted, while a band or chain 18 is substituted. This band unites the power and brake rods. To enable the same effect to be produced as hereinbefore described—viz., to shut off the 30 power by the application of the brakes—I have made the band 18 of such length that considerable slack exists, this slack being taken up by a spring 19 or its equivalent. As shown in Fig. 1, the power is shut off and the brakes 35 free. Consequently no part of the chain is wound either about the power-rod or the brake-rod and the slack is held by the spring 19. Assume that the car is to be started. Rotation of the power-rod 4 causes one or more turns of 40 chain to be made thereabout, and this remains so coiled until the brakes are applied by rotation of the brake-rod. Such movement coils the chain in part about said brake-rod and uncoils that about the power-rod, 45 thus actuating the latter, and the same effect is produced as when a brake-drum is used and a chain unites the brake-rod with said drum. Conversely, presuming the power has been shut off by application of the brakes, when 50 the latter are released part of the chain wound about the brake-rod is uncoiled, and this slack is taken up by the spring 19. Thus the power can be applied without being influenced

by the brake-rod; but any movement of the latter in setting the brakes serves to operate 55 the rheostat-lever and diminishes the power, provided the power is then applied. The same result is thus accomplished as by the arrangement first described.

It may be added that the resistance of the 60 spring 19 is sufficient to cause either the power or brake rods, when the chain is passing about them, to actuate the mechanism connected with them in lieu of yielding and permitting the slack to be coiled up without 65 operating the parts intended to be moved. The brake-drum rotates in direction of arrow 1 (see Fig. 3) when the brake is applied, and the power-drum oppositely (see Fig. 3, arrow 2) when the power-rod is moved to start the 70 motor.

What I claim is—

1. The combination, with the revoluble power-rod, a rheostat, and its lever by which resistances are thrown in or out, of a revoluble 75 brake-rod and mechanism, as a chain, by which the rheostat-lever is positively interconnected and operated separately by the power-rod or by the brake-rod, substantially as described.

2. In an electric car, a fixed rheostat, a shaft carrying two revoluble drums, a brake-rod and a power-rod respectively operating said drums, means for causing the latter to engage at certain points in their revolution, 85 and a rheostat-lever actuated both by the power and by the brake shafts, substantially as herein stated.

3. The combination, with the rotary power and brake rods 4 and 5, of the rod or shaft 8, 90 fixed to the bottom of the car, the brake and power drums 9 and 13, loosely mounted on said shaft and provided with engaging abutments or shoulders 17 18, the regulating arm or lever 15, connected with the said power- 95 drum to move therewith, and the bands or chains 10 14, connecting the said brake and power shafts with the said brake and power drums, as set forth.

In testimony whereof I affix my signature in 100 presence of two witnesses.

BELLVILLE L. RANDALL.
